UNITED STATES PATENT OFFICE.

NELS NELSON, OF SPOKANE, WASHINGTON.

SALVAGING EQUIPMENT.

Application filed September 4, 1928. Serial No. 303,870.

My present invention relates to an improved salvaging equipment for use in raising sunken or submerged ships or vessels to the water surface. In carrying out the salvaging operations for a sunken ship, after the latter has been properly located, I utilize a pair of salvaging or rescue ships of suitable floating capacity, one located at each side of and parallel with the sunken vessel, and from the surface vessels lifting hooks and cables are lowered. A diving bell is utilized in connection with the salvaging operations, and by proper signals from the diving bell to the deck of the salvaging ships the lifting hooks are manipulated from the decks of the ships, and caused to be engaged with the walls about holes, as portholes in the hull of the sunken ship, or with other objects on the ship that will support the hooks, in order that the sunken ship may be raised to the surface. A plurality of the salvaging or lifting hooks are used along each side of the sunken ship, said hooks being lowered one after another and secured to the hull or other part of the ship, and a supporting table is temporarily employed for the lifting hook as it is being attached to the sunken ship. The manipulating, adjusting, and control of the operating parts of the hooks are all under control of men on the salvaging ships who are directed by signals from the man in the diving bell.

The invention consists in certain novel combinations and arrangements of parts of the lifting hook whereby it is attached to the supporting part of the ship to be lifted, and in other combinations and arrangements of parts co-operating with the hook or hooks as will hereinafter be more fully pointed out and claimed.

In the accompanying drawings I have illustrated one complete example of the physical embodiment of my invention where-in the parts are combined and arranged according to the best mode I have thus far devised for the practical application of the principles of my invention.

Figure 1 is a view looking toward the bows of the two salvaging ships and the sunken ship, with the lifting hooks attached to the starboard side of the sunken ship and showing the lifting hooks being attached at the port side of the ship, the lifting cables being suspended from an overhead beam or girder coupling the two salvaging ships, and

the diving bell, as well as the hook supporting table are also illustrated.

Figure 2 is a view as at line 2-2 of Figure 1.

Figure 3 is an enlarged perspective view of one of the lifting hooks.

Figure 4 is a side view partly broken away showing the manner of laterally moving a lifting hook through a port hole to secure a lifting engagement with the upper wall or edge of the port hole.

Figure 5 is a view similar to Figure 4 but with the hook in engaged and lifting position, and showing the supporting table being lifted to the deck of one of the salvaging ships.

Figure 6 is a top plan view of the hook-holder used while the hook is being moved into operative position.

In order that the general assembly, arrangement of the ships, and utility of various parts of the equipment may readily be understood I have shown in Figure 1 the sunken ship S assumed to be resting on the bottom of the river, harbor, sea, or ocean and the two salvaging vessels A and B are in position for supporting the hoisting mechanism by means of which the various submarine devices are lowered and raised as well as for supporting the hoisting machines for the sunken ship. The two salvaging ships are tied together by a suitable number of transversely arranged, spaced beams or girders or trusses T that span the space between the salvage ships and above the sunken ship, and these trusses are pivotally connected, as at P with frames F of the salvaging ships in such manner as to permit relative movement of the two salvaging ships on the water surface, it being understood of course that the two salvaging ships are anchored in suitable manner to prevent their displacement from operative relation to the sunken ship.

A diving bell D, suspended by cable C, and provided with proper telephonic connections, signal apparatus, and other necessary equipment for communicating with the men on the deck of the salvaging ships, is lowered from the deck of the suspending ship in position for use adjacent the sunken ship.

When available, the port holes H, or the walls surrounding the port holes, are used for attaching or connecting the lifting hooks indicated as a whole by the numeral 1, or

these hooks may be applied to other parts on the hull or to other parts of the ship for lifting the latter, the hooks of course being located at proper points along both sides of the sunken ship to hold her on an even keel as it is being lifted to the surface of the water.

The lifting hooks are suspended from cables 2 by links 2' and these cables pass over 10 guide pulleys 3 on the overhead truss T, and thence to the hoisting mechanism, indicated as 4, positioned on the decks of the two salvaging ships. The hooks are of similar construction and a description of one 15 will suffice for all of them.

A single horn as 5 forms the hook element for engagement with the wall of the porthole, and this horn is fashioned integral with a cylindrical bushing 6 that is provided with a lever 7 projecting from the 20 bushing at the side opposite to the horn.

At the opposite ends of the bushing are provided clutch teeth 8 and 9 formed in 25 annular series and forming parts of two clutches for alternate use in connection with the hook. The bushing surrounds and is supported on a clutch bar 10 having screw threads at its opposite ends, and two clutch links 11 and 12 suspend the clutch bar. 30 These links have clutch teeth 13 and 14 for co-action with the respective teeth 8 and 9 on the bushing, and the links are slidably supported on the opposite ends of a swivel bar 15 located parallel with and above the clutch bar. The bushing, when disengaged from both clutch links, is free to rock on bar 10, but has no longitudinal movement. Keys 17 and 18 co-act with the links and the 35 swivel bar to prevent relative turning of these members and permit lateral movement of the links relative to the swivel bar so that the clutch members of the links may, selectively, be moved toward the bushing for clutch engagement with its teeth, so that the bushing may be held rigid with the 40 swivel bar, when the horn of the hook is engaged with the port hole of the ship.

An eye bolt 18 is swiveled in a bearing 19 of the swivel bar, and a nut 20 beneath the bearing 19 holds the eye-bolt against displacement. The link 2' is connected to the eye-bolt and the lifting cable 2, as shown, is connected to this link.

Two rotary, clutch drums 21 and 22 are 50 carried on the opposite, threaded ends of the clutch bar and these drums perform the functions of traveling nuts that are movable between the outer faces of the respective links and stop pins 23 passed transversely 55 through the opposite ends of the clutch bar. The drums are turned by power through the medium of a pull on a clutch cable, as 60 24, wound upon each of the drums, and the pull is applied by suitable winding mechanism on the deck of the salvage ship. By

turning one of the drums on the threaded clutch bar the drum is moved into frictional contact with a link, and by a continued turn of the drum the link is pushed to bring its clutch teeth in engagement with the complementary teeth on the clutch bushing, and the drum and link are thus frictionally engaged to lock the clutch members.

Before being lowered to the proximity of the sunken ship, the hook device is applied 75 to a supporting table 29 from which the hook is supported while being adjusted. For this purpose the two links of the hook are fashioned with brackets 25 that co-act with a hook holder comprising a yoke 26 having 80 sockets 27 for the brackets, and a screw bar 27' rigid with the holder-yoke is longitudinally slidably through a bearing sleeve 28 that is fixed to the top of the table 29.

This table has adjustable, telescopic legs 85 30 that may be adjusted to compensate for irregularities in the surface that supports the table, as indicated in Figure 4, so that the top of the table may be approximately leveled, and the hook, with its holder is 90 adapted to be moved laterally of the table along the longitudinal axis of the bearing sleeve 28. The table is lowered by means of a cable 31, and suitable lowering mechanism on the deck of the salvaging ship, and the 95 screw bar 27' is provided with a non-traveling, rotary nut or drum 32 that is rotatably anchored to a bearing member 33 rigid with the bracket 34 secured to the table. A cable 35 is wound upon the drum, and by pulling 100 either end, from suitable mechanism supported on the deck of a salvaging ship, the cable causes the drum to turn on the screw bar of the holder moving said screw bar to the right or left in Figure 4. Thus the 105 holder may be shifted to the left as indicated in Figure 4 to move the hook or its horn 5 to the lifting position of Figure 5, and when the lifting pull is applied to cable 2, the hook is lifted to operative position in Fig. 5. 110 Before the cable 2 is made taut however, and after the holder has been projected to bring the horn to proper position with relation to the port hole, the horn is turned to hooking position, i. e. turned from position of Figure 115 4 to that of Figure 5, after which the horn is locked by the clutch members as described. For turning the horn to hooking position of Figure 5 I employ a cable 36, and a pulling device on the deck of the salvaging ship. 120 The cable is passed under a guide pulley 37 on one side of the table and connected to the lever 7 of the bushing, and as the guide pulley is below the lever, a pull on the cable or cord depresses the lever and elevates the 125 horn as in Figure 5.

After the hook has been properly placed and its cable 2 is secured, the holder is withdrawn from the brackets 25, and then the table 29 is lifted by using the hoisting cable 130

31, as indicated in Figure 5, after which the table and another hook are lowered and the succeeding hooks are placed in position, the table being alternately lowered and elevated 5 and the holder being operated for the placement of the hooks.

After all of the hooks have been placed at the opposite sides of the sunken ship, the hoisting mechanisms for the various cables 2 10 are operated and the hooks form a cradle for lifting the ship on an even keel. When the ship has reached the surface and is floated, the numerous hooks are disengaged from the portholes and gathered on shipboard for 15 future use.

Having thus fully described my invention, what I claim as new and desire to secure by Letters Patent is:—

1. A salvaging equipment for use with a 20 sunken ship and a pair of salvaging ships comprising transversely arranged trusses having pivotal connection with the salvaging ships and spanning the space over the sunken ship, hoisting cables suspended from said 25 trusses and hooks at the ends of said cables, means for holding the hooks and means for moving said holding means to bring the hooks to operative relation to the sunken ship.
2. A salvaging hook for use as described comprising a clutch bar, a horn having a non-slidable bushing pivoted on the bar, a

swivel bar and clutch links on the swivel bar for supporting the clutch bar, and means for selectively moving said links to lock the 35 clutches for rigidly holding the bushing and swivel bar.

3. The combination with a swivel bar and a pair of laterally movable clutch links, of a clutch bar suspended in the links, a pivotal, 40 non-slidable clutch bushing between the links and provided with a hook-horn, and means for moving said links to clutch engagement with the bushing.

4. The combination with a swivel bar and a pair of laterally, movable clutch links 45 slidable on the bar, of a clutch bar suspended in the links and provided with screw-threaded ends, a pivoted clutch bushing on the clutch bar between the links, a hook-horn on the bushing, and a pair of rotary drums on the threaded ends and operating means therefor for moving the links into clutch engagement with the bushing.

5. The combination with a salvaging hook 55 and its suspending cable, brackets on the hook and a supporting yoke for engagement with the brackets, of a screw bar rigid with the yoke, a support and a bearing sleeve thereon for the screw bar, a non-traveling 60 nut on the screw bar, and means connected with the table for anchoring the nut.

In testimony whereof I affix my signature.
NELS NELSON.
